UNITED STATES PATENT OFFICE.

ODIS RALEY AND GRAHAM APPERSON, OF PARAGOULD, ARKANSAS.

SWITCH.

Application filed April 8, 1922. Serial No. 550,652.

This invention relates to a signal for motor vehicles, the general object of the invention being to provide a signal lamp with means for igniting the same when the vehicle 5 is to be backed.

Another object of the invention is to provide a novel form of switch which is moved to close the circuit of the lamp when the gear shift lever is moved to reverse position.

0 This invention also consists in certain other features of construction and in the combination and arrangement of the several parts, to be hereinafter fully described, illustrated in the accompanying drawings and 5 specifically pointed out in the appended claim.

In describing the invention in detail, reference will be had to the accompanying drawings wherein like characters denote like or corresponding parts throughout the several views, and in which:—

Figure 1 is a diagrammatic view of the invention applied to an automobile having a transmission of the sliding rod type.

Figure 2 is a similar view showing the invention applied to an automobile equipped with a reverse pedal.

Figure 3 is a side elevation of the switch per se.

Figure 4 is a longitudinal vertical sectional view therethrough.

Figure 5 is a transverse sectional view.

Figure 6 is a detail view of one of the spring contacts.

In these views 1 indicates a signal lamp which is placed at any desired position on the rear part of the motor vehicle. This lamp is of substantially fan shape so as to give a wide beam of light. The bulb in this lamp is electrically connected with any suitable source of supply, as shown at 2, and a switch 3 is located in the circuit to control the same. As shown this switch comprises a cylinder 4 which has one end closed and the other end screw threaded to receive a screw threaded cap 5. A pair of converging spring contacts 6 are placed in the cylinder, the terminals 7 of which extend through the cylinder and are suitably insulated therefrom. These terminals have the ends of the conductors suitably secured thereto. A piston 8 is arranged in the cylinder, and includes a disk of non-conducting material and a ring of conducting material is carried by these parts and projects beyond the same so as to electrically connect the two contacts

together when the piston has been moved inwardly. The piston also includes a pair of washers formed of insulating material and one of said washers is recessed to accommodate the disk in a manner to secure the same between said washers and so that the disk is insulated from a relatively long rod 9 which passes through the cap 5 and has a washer 10 on its outer end which forms a seat for a spring 11 which has its other end bearing against a part of the cap. The switch is so positioned that the end of the rod 9 will be struck by the projecting end of the sliding rod 12 of the transmission 70 means when the shift lever 13 is moved into reverse position. When the lever is in this reverse position the part 12 will engage the end of the rod 9 and thus force the same inwardly against the action of the spring 11 75 and so place the piston in engagement with the spring contacts, thus completing the circuit through the switch and permitting current to pass to the lamp. As soon as the shift lever is moved to neutral or any other 80 position besides reverse, the rod will be forced outwardly by the spring and thus move the piston out of engagement with the contacts and thus break the circuit to the lamp.

It will be seen that the switch can be used on all types of cars, and with all types of transmissions. When it is used on the Ford type the rod 9 is placed where it will be pushed inwardly by the reverse pedal so 90 that it is simply a matter of properly positioning the switch to make it operable on any type of car or transmission.

It is thought from the foregoing description that the advantages and novel features 95 of the invention will be readily apparent.

We desire it to be understood that we may make changes in the construction and in the combination and arrangement of the several parts, provided that such changes fall within 100 the scope of the appended claim.

What we claim is:—

A switch of the character described comprising a cylinder, a pair of converging contacts fixed at their remote ends in the cylinder and being insulated therefrom, a cap for one end of said cylinder, a relatively long rod passing through said cap and having one end terminating in said cylinder, a piston secured to the last mentioned end of 110 said rod and including a pair of washers of insulating material, a disk of conducting

material arranged in a recess formed in one of said washers and held therein by the other of said washers, said disk being adapted to bridge the adjacent end portions of converging spring contacts for a wiping engagement therewith, a spring surrounding the rod for normally holding the disk out of engagement with converging contacts, and the outer end of said rod being adapted to lie in the path of a movable part of an auto-

mobile transmission in a manner whereby said part is adapted to move said rod against the tension of said spring to provide the wiping engagement of the disk with the contacts.

15

In testimony whereof we affix our signatures.

ODIS RALEY.
GRAHAM APPERSON.
